UNITED STATES PATENT OFFICE.

WALTER S. ADAMS, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

CAR-TRUCK.

1,076,009.

Specification of Letters Patent.

Patented Oct. 14, 1913.

Application filed June 18, 1913. Serial No. 774,286.

To all whom it may concern:

Be it known that I, WALTER S. ADAMS, a citizen of the United States, and a resident of the city and county of Philadelphia, 5 State of Pennsylvania, have invented new and useful Improvements in Car-Trucks, of which the following is a specification.

My invention has relation to improvements in the bolster support in "maximum-traction" or eccentrically pivoted trucks, in which, among other things, considerable clear space within the truck frame is required for the mounting of the truck bolster, etc., near the driving wheels; although 15 my improvements may be advantageously employed in other relations, and other forms of trucks.

One of the objects of my invention is to provide a suitable bolster support in car trucks, so that it may be suitably supported during all the conditions of service. To obtain this result it is desirable to use both leaf and spiral springs, so that the slow action of the leaf springs will be combined 25 with the quick action of the coiled springs to produce an easy riding truck.

Particularly, the object of my invention is in part to provide a combination of this sort where the links for supporting the leaf 30 springs are preferably outwardly splayed to obtain a long or extended spring base, and a coil spring is placed between the bolster and the leaf spring, and suitable mechanism is provided which will keep the coil spring 35 from being subjected to excessive stresses which will tend to deform or injure it, or to interfere with its proper action. This, and other objects, are accomplished by my invention, one embodiment of which is here- 40 inafter set forth.

For a more particular description of my invention, reference is to be had to the accompanying drawings, forming a part here- 45 of, in which—

Figure 1 is a side elevation of a portion of a truck provided with my improvement. Fig. 2 is a plan view of a part of the same; Fig. 3 is a sectional view taken on the line 3—3 of Fig. 2, looking in the direction of 50 the arrows; Fig. 4 is a sectional view, taken on the line 4—4 of Fig. 2, looking in the direction of the arrows; Fig. 5 is a sectional view taken on the line 5—5 of Fig. 1, looking in the direction of the arrows; Fig. 6 is

a sectional view taken on the line 6—6 of Fig. 5, looking in the direction of the arrows; Fig. 7 is an inverted plan view of a portion of the bolster; Fig. 8 is a plan view of a portion of the bolster; Fig. 9 is a sectional view taken on the line 9—9 of Fig. 8, 60 looking in the direction of the arrows; and Fig. 10 is a sectional view, taken on the line 10—10 of Fig. 5, looking in the direction of the arrows.

Throughout the various views of the drawings, similar reference characters designate similar parts.

My improved truck 1 is provided with suitable wheels 2 and 3 which, in the embodiment shown, are suitable wheels for a maximum traction truck, it being understood that for any other form of truck, suitable wheels will be provided. These wheels are mounted on the usual axles 4 and 5 respectively, which are connected by journal boxes of the conventional form to the pedestals 6 and 7 of the usual type, and these pedestals are connected by a suitable top cord and a tie-bar 9, or by any other suitable means. The top cord 8 has seats 10 which carry links 11, of the usual type, (preferably splayed outwardly to increase the lateral spring base) and these links are connected by a leaf spring 12 provided with a strap 13 which may be of any desired form. The 85 ends of the spring lie on and engage blocks 11^a, which are flanged to engage the links 11, and inclined at 11^b to allow for the deflection of the spring 12.

Surmounting the strap 13 is a spring-seat 14 of a novel form. This seat 14 has a laterally and radially extending perforated ear 15, the purpose of which will be described below. In the seat of this spring cap or seat 14 is a suitable coiled spring 16 which is 95 surmounted by a second cap or seat 17 fixed to a bolster 18. This bolster 18 is preferably provided with a top flange 19 and a bottom flange 20 connected by a suitable web 21 which extends from one spring cap 17 to 100 the other. The other flange 19 is surmounted by suitable side bearings 22 and a center bearing 23, and a suitable opening 24 is made in the webs 21, 19 and 20 for the king bolt.

Each side bearing 22 has a suitable rubbing surface 25 to support the car and other surfaces which are adapted to engage suit-

able rub plates 26 carried by the transom 27, and other parts which engage a U iron 28 secured to the transoms 27 adjacent to the top cord 8. The transoms 27 and top cord 5 28 are reinforced by means of suitable gusset plates 29, which are bolted or otherwise secured in place.

The perforated lugs 15 receive pins 30, which pins 30 engage paired links 31 which 10 run to corresponding perforated lugs 32 which are integral with the web 20 in the preferred embodiment of my invention. These lugs 32 are provided with suitable pins or bolts 33 which also pass through 15 suitable registering perforations in the links 31 and pivotally connect these links with their respective lugs. The links 31 prevent the spring-seats 14 from approaching each other, or otherwise becoming displaced but 20 do not interfere with the slight vertical movement of these seats when the truck is in use or the endwise movement of the bolster, 18 as they move laterally in unison with the bolster. The omission of these bars 31 25 would cause the springs 16 to become unduly distorted when the device is in use, because of the play of the hangers 11 and bolster.

When one of my improved trucks, made as above described, is in use, the load on the 30 bolster is transmitted to the springs 16 and from thence to the springs 12 and thence to the hangers 11. When there is any shifting due to irregularities in the track or load, there is no tendency on the part of the bolster to unevenly twist the spring 16, because 35 the bars 31 force the spring 12, 16, to remain in parallel relation with each other and in proper relation to the bolster 18.

As above stated, the particular combination 40 of the leaf spring and superposed spiral spring entering into the support of the bolster is advantageous; but for the full realization of all the benefits that I desire to secure from the construction described, I prefer to 45 so design the spiral springs 16 that they will normally support the load of the car body and seated passengers, or a normal car-load, without undue settling, leaving a sufficient range of release or expansion in them to accommodate 50 variations in the excess of the above load. The reason for doing this is that the capacity and resiliency of these springs, as spiral springs, will be present under all conditions of normal load. In order 55 to avoid the possibility of these springs going solid under the existence of excessive load, they are so arranged that the spring seat 17 may come into contact with the seat 14, under an excess load which will relieve the spiral springs of the excess of the load, 60 which will then be borne by the slower acting leaf spring 12. When this happens, the coils of the springs 16, as designed, are not closed. If the coils came together solid, 65 there would be a tendency for the springs to

crystallize and break; whereas, by so apportioning their range of compression with the range of movement between the two spring seats that the latter will come together and bear the excess of the load, before the 70 springs have become solid, the designed capacity of these springs is retained and their capacity for coming back into the above duty automatically arranged for. I believe this arrangement to be entirely new and, 75 therefore, do not limit myself to the exact details of construction or combination of elements shown and described herein.

While I have shown and described one embodiment of my invention, it is obvious 80 that it is not restricted thereto, but is broad enough to cover all structures that come within the scope of the annexed claims.

What I claim is:

1. In a car truck, the combination with 85 a truck frame, paired bolster-supports at each side of the truck and carried by the truck frame, longitudinally disposed springs extending between and supported by each pair of said bolster supports, other springs mounted on said first mentioned springs, and a bolster supported on the latter springs.

2. In a car truck, the combination with a truck frame, hangers, leaf springs carried 95 by the hangers, spiral springs mounted on said leaf springs, and a bolster supported on said spiral springs.

3. In a car truck, the combination with a truck frame having side bars, hangers thereon, longitudinally disposed leaf springs supported from the side bars by the hangers, 100 springs on the leaf springs and a bolster supported on the latter springs.

4. In a car truck, the combination with a truck frame having side bars, hangers thereon, leaf springs supported by the hangers and longitudinally disposed with their arch upward, springs on the arch of the leaf springs, and a bolster supported on the latter 110 springs.

5. In a car truck, the combination with a truck frame having side bars, hangers thereon, longitudinally disposed leaf springs supported by the hangers from the side bars, 115 spiral springs on the leaf springs and a bolster supported on said spiral springs.

6. In a car truck, the combination with a truck frame, hangers, leaf springs carried by the hangers, spiral springs supported on 120 the leaf springs, a bolster supported on the spiral springs, and means carried by the bolster and leaf springs for permitting a predetermined amount of load to be primarily carried on the spiral springs and the excess 125 load on the leaf springs.

7. In a car truck, the combination with a truck frame, hangers, leaf springs carried by the hangers, spring seats on the leaf springs, spiral springs on said seats, a bol- 130

- ster having spring seats engaging said spiral springs, said seats being adapted to come together when a predetermined load on the spiral springs has been exceeded.
- 5 8. In a car truck, the combination with a truck frame, hangers thereon, leaf springs on the hangers, spiral springs supported on the leaf springs, a bolster carried by the spiral springs, the spiral springs being adapted to carry a predetermined load and yield to an excessive load without closing and means carried by the bolster and leaf springs for taking up the excess of said load.
- 10 9. In a car truck, the combination with a truck frame, hangers thereon, longitudinally disposed leaf springs supported by the hangers, spiral springs supported upon the crowns of said leaf springs, a cross truck bolster supported on said spiral springs and means combined with the leaf springs and bolster for taking up the excess load imposed on the spiral springs.
- 15 10. In a car truck, the combination with a truck frame, bolster-supports carried by the truck frame, springs supported by said bolster supports, springs mounted on said first mentioned springs, a bolster supported on the latter springs, and means for movably securing the bolster and the first mentioned springs together and restraining them from transverse displacement while permitting a relative movement between the bolster and said first mentioned springs in a plane perpendicular to the longitudinal axis of the bolster.
- 20 11. In a car truck, the combination with a truck frame, hangers thereon, longitudinally disposed leaf springs carried by the hangers, spring seats on the crowns of the leaf springs, spiral springs seated in said seats, a cross bolster, spring seats thereon for receiving the spiral springs, and means for movably connecting the leaf spring seats and bolster spring seats.
- 25 12. In a car truck, longitudinally disposed leaf springs, hangers supporting the same, means for supporting the hangers, a cross bolster, spring seats on the leaf springs, means for movably connecting the bolster and spring seats together and other springs interposed between the bolster and said spring seats.
- 30 13. In a car truck, the combination with a truck frame, hangers, longitudinally disposed leaf springs supported on the hangers, spring seats on the leaf springs, a bolster, articulated devices connecting the bolster and spring seats and springs interposed between the spring seats and the bolster.
- 35 14. In a device of the class described, splayed links and means for supporting the same, leaf springs connecting said links, a bolster, springs between said bolster and the leaf springs, and means connecting said bolster and leaf springs whereby said springs are prevented from approaching each other.
- 40 15. In a device of the class described, splayed links and means for supporting the same, leaf springs connecting said links, spring seats on said springs, a coiled spring on each of said seats, a bolster supported by said coiled springs, and means connecting said bolster and leaf springs, so that said leaf springs are prevented from approaching each other.
- 45 16. In a device of the class described, a leaf spring, a bolster, and a bar connecting said spring and bolster so that said leaf spring is prevented from approaching the center of the bolster.
- 50 17. In a device of the class described, splayed links and means for supporting the same, leaf springs connecting said links, bands on said springs, a spring seat on each of said bands, a lug extending from each of said seats, a coiled spring on each of said seats, a bolster supported by said coiled springs, and bars connecting said bolster with a pivotal connection with said first mentioned seat so that said leaf springs are prevented from swinging toward each other, and the links or hangers are held in a splayed position.
- 55 18. In a device of the class described, splayed links and means for supporting the same, leaf springs connecting said links, bands on said leaf springs, spring seats on said bands, a coiled spring on each of said seats and a bolster supported by said coiled springs, and means connecting said bolster and leaf springs so that the coiled springs are kept from undue stresses when the device is in use.
- 60 19. In a device of the class described, a bolster with a downwardly depending lug, a spring seat with a laterally and radially extending lug, a bar connecting said lugs and bolts passing through said lugs and bar.
- 65 20. In a device of the class described, a pair of splayed links and means for supporting the same, a leaf spring connecting said links, a bolster, a coiled spring carried by said leaf spring and supporting one end of said bolster, and means for preventing said coiled spring from being twisted when the device is in use.
- 70 Signed at the city of Philadelphia, county of Philadelphia, and State of Pennsylvania, 120 this 14th day of June, 1913.
